UNITED STATES PATENT OFFICE.

CHARLES T. COE, OF KEARNEY, NEW JERSEY, ASSIGNOR, BY MESNE ASSIGNMENTS, TO DIAMOND POWER SPECIALTY COMPANY, OF DETROIT, MICHIGAN, A COPARTNERSHIP COMPOSED OF RAPHAEL HERMAN AND SAMUEL J. HERMAN.

TUBE-CLEANER.

1,348,542.

Specification of Letters Patent. Patented Aug. 3, 1920.

Application filed June 3, 1911. Serial No. 631,105.

To all whom it may concern:

Be it known that I, CHARLES T. COE, a citizen of the United States, and a resident of Kearney, in the county of Hudson and 5 State of New Jersey, have invented certain new and useful Improvements in Tube-Cleaners, of which the following is a specification.

This invention relates to an attachment 10 for water tube boilers of a character adapted more particularly to cleanse the tubes or flues of the boiler of accumulated ash and soot.

The type of water tube boiler for which 15 the present invention is specifically designed is what is known in the art as the inclined tube type, that is to say, the tubes extend obliquely from the fire box upward or vice versa, according to the particular type of 20 boiler. These tubes are arranged in horizontal rows, and in order to relieve the same from accumulated material, it has been the practice to project blowers through the side walls of the furnace structure.

25 In carrying out this process, it was the practice to position the blower in one opening of the boiler wall and after a partial cleansing operation, remove the same and position it in another of the openings, and 30 so on until the cleaning operation was complete. It has been ascertained that this mode of cleansing has involved some considerable time, and the results were not altogether satisfactory, for the reason 35 among others, that the hand of the operator was dependent upon to shift and properly position the nozzle with respect to the tubes, and in many instances it was found that the cleansing operation was not as 40 effective as necessity demands.

It is contemplated by the present invention, and the primary object of the invention may be briefly stated, to provide a series of blower elements or nozzles, one for 45 each of the openings in the boiler wall, and a nozzle of the series being arranged in line with the space between the different layers of inclined tubes, with means whereby said nozzles may be operated simultaneously with the result that all of the horizontal rows or layers of tubes may be 50 cleansed at the one operation.

It is a further object of the invention to provide in combination with a water tube

boiler having in one wall thereof a vertical 55 series of openings, of a set of nozzles arranged one above the other in vertical series adapted to project through said openings, the parts being constructed and arranged whereby said series of nozzles are adapted 60 to move in the general inclined direction of the tubes, and whereby the nozzles move in planes oblique to the vertical arrangement thereof.

A further object of the invention is to 65 provide means whereby the vertical series of nozzles within the openings of the boiler wall are effectively guided in their movement in the general direction of the inclined tubes together with means whereby the 70 series of nozzles will remain in the same relative vertical plane throughout the movement thereof.

Still other and further objects and improvements, and novel details in the construction and arrangement of the various parts of the invention will be appreciated from the description to follow, which for a better understanding of the invention is to be considered in connection with the accompanying drawings, which form a part 75 hereof, and wherein is disclosed for the purpose of illustration, convenient and satisfactory embodiments of the invention.

In the drawings:—Figure 1 is a side elevation of a boiler with my improvements applied thereto, Fig. 2 represents an enlarged fragmentary section of Fig. 1 as on the line 2, 2, Fig. 3 shows an enlarged fragmentary portion of Fig. 1, Fig. 4 represents 80 a side elevation of a boiler with a modified form of the invention, Fig. 5 is a section of Fig. 4 as on the line 5, 5, Fig. 6 shows an enlarged section of Fig. 4 as on the line 6, 6, Fig. 7 represents an enlarged fragmentary 85 portion of Fig. 5 and Fig. 8 is a section as on the line 8, 8 of Fig. 7.

Referring particularly to Figs. 1 to 3 a boiler 15 is shown with the inclined tubes 16 and the usual cleaning frames 17, each 100 of the latter having the tapering sides 18, roof 19 and base plate 20. Guards 21 extend from each roof and base plate. To the frames are hinged new and novel cleaning doors each preferably comprising the members 23, 24. The said members have respectively formed therewith side flanges 25, 26, top flanges 27, bottom flanges 28 and accom-

panying flanges 29, the latter being connected by clamping bolts 30. The flanges 29 are formed with spherically shaped bearings 35 forming openings in the members 23, 24 of the cleaning doors and spherical covers 36 may be hinged to the cleaning door over the openings of the bearings 35.

- 5 Balls 40 having axial openings therethrough are supported in the bearings 35.
- 10 A main steam supply pipe 41 has extending therefrom the branch outlet pipes 42 to which latter are connected the valves 43. Flexible conduits 44 are coupled to the valves 43 and extend to the adjustably supported stand pipes 45, from which latter extend outlet nipples 46 having the vent openings 47 and valves 48. The outlet nipples enter the openings in the balls 40.

- 15 A clamping ring 50 surrounds each adjustably supported stand pipe 45 and a spring 51 connects each of said rings with its accompanying cleaning door. A pair of clamping rings 54, 55 are bolted to each stand pipe 45, and one of the members of 20 each of the latter clamping rings has extending therefrom a lug 56 with a guide opening for a supporting spindle 57. The spindle 57 has a forked end 58 which carries a pin 59 for a supporting roller 60, which bears on the base plate 20. A collar 61 is fastened to the spindle 57 and a spring 62 bears between the collar 61 and the lug 56 of the clamping ring 54.

- 25 A supporting spindle 65 with the roller 66 may be connected up with the upper portion of each stand pipe 45, the rollers 66 bearing up against the roof 19.

- 30 To operate the invention steam or compressed air is delivered from the supply pipe 41 and enters the conduits 44, to flow into the stand pipes 45, and from the latter escapes into and through the outlet nipples 46. From the nipples 46 the fluid enters the boiler between the tubes 16 which 35 are thereby cleaned. The operator by moving the supporting spindles 57 can move the nipples along the inclined spaces between the flues of the boiler, by virtue of the adjustments of the balls 40 in their bearings 40 55 and the flexibility of the spring 62, by means of which all portions of said tubes are cleaned. The springs 51 tend to maintain the nipples 46 within the boiler and the guards 21 prevent the nipples 46 from disengaging from the balls 40. It will be observed that the stand pipe is provided with a handle whereby the same may be depressed or elevated, as manipulating conditions require, and in the normal position of the parts, because of the interposed spring member or members 51, the nozzles 46 will be held projected into the furnace, as shown at the top of Fig. 2, but may be withdrawn from the furnace as shown at the bottom 60 65 portion of said Fig. 2. The roll 60 enables

the stand pipe to move on the base 20 as the operator wills. In order to cause the nozzles which are flexibly connected to the stand pipe 45, to follow the line of tubes, they are projected to a point where they are 70 located between two of the first vertical tier of tubes as shown more particularly in Fig. 5. Therefore, as the stand pipe is operated by moving either to the right or to the left, the nozzles owing to their flexible connections and universal bearing through the boiler provided by the ball joint will be guided by the first two tubes and caused to move and follow the direction of the tubes. In other words, the nozzles, as a series, may 80 be moved so as to direct the sprays issuing therefrom over a wide area and the direction of movement is covered by the tubes of the first vertical tier.

85 In the modification of the invention a similar boiler is represented at 70 with the inclined tubes 71 and the cleaning frames 72, with the inclined sides 73, roofs 74, and base plates 75. The sides 73 are connected by the vertical connecting member 74 which has 90 formed therewith the openings 76 and flanges 77. Doors 78 for the openings 76 have trunnions 79 which are located in the guides 80 in the usual way.

95 In each of the openings 76 are located the members 85, 86 of a spherical bearing. Screws 87 connect the members 85, 86 and screws 89 clamp the bearings to the connecting members 74. Balls 90 each with an axial opening are supported in the spherical 100 bearings. Semi-spherical covers 91 are hinged to the members 85 of the spherical bearings.

105 A main steam supply pipe 92 has extending therefrom branch outlet pipes 93, to which latter are connected valves 94. Flexible conduits 95 are coupled to the valves 94 and extend to the stand pipes 96.

An operating handle 97 and guide rollers 98 extend from each stand pipe 96. Inclined guide rails 105, 106, are pinned to the inclined sides 73 and support the rollers 98. Each of the stand pipes 96 carries a swinging joint 107 and from each of the latter extends an outlet nipple 108, which 110 leads the steam or other fluid into the boiler between the flues. The operation of this modification of the invention is evident from the description of its parts, and it will be noted that the inclined guide rails 105, 106 115 direct the nipples along the inclined spaces between the tubes of the boiler. In this embodiment of the invention the boiler tubes themselves need not be depended upon as the guiding means for causing the nozzles to 120 follow the general inclination of the tubes.

125 Vent openings 110 are formed in the nipples 108. The vent openings 110, as well as the vent openings 47, allow the circulation of air in their respective nipples, when the

covers 36 and 91 cover the ends of said nipples.

Having described my invention, what I desire to secure by Letters Patent and 5 claim is:

1. In a tube cleaner for a boiler the combination of a supply pipe, a flexible conduit extending from said pipe, an adjustably supported stand pipe connected to the conduit, a ball supported in a bearing on the side of the boiler and an outlet nipple extending from the said stand pipe through said ball, said stand pipe being adapted in its movement to impart longitudinal as well 15 as lateral movement to the outlet nipple.

2. In a tube cleaner for a boiler the combination of a supply pipe, a flexible conduit extending from said pipe, a stand pipe connected to the conduit, a ball supported in 20 a bearing on the side of the boiler, an outlet nipple extending from the stand pipe, a supporting spindle for the stand pipe, and a flexible connection between the said spindle and stand pipe to allow the nipple to move 25 in an inclined direction when the supporting spindle moves on a horizontal plane.

3. In a tube cleaner for a boiler the combination of cleaning frames in the side of the boiler, cleaning doors hinged to each 30 frame, spherical bearings formed in the doors, a ball having an axial opening in each bearing, a stand pipe opposite each door, outlet nipples carried on each stand pipe extending through said balls, a base plate 35 for each frame, supporting spindles flexibly

connected with each stand pipe, supporting rollers for each of said spindles bearing on their accompanying base plate.

4. In a tube cleaner for a boiler the combination of a number of cleaning frames in 40 the side of the boiler, a cleaning door comprising a pair of members bolted together and hinged to each of said frames, spherical bearings formed with the members of each door, a ball having an opening supported in 45 each bearing, a stand pipe for each door, a base plate extending from each frame, clamping rings on each stand pipe, lugs extending from the ring, a supporting spindle guided in said lugs and supported on the 50 base plate, a supporting collar on each spindle, a spring bearing between said collar and one of said lugs, and outlet nipples carried on the stand pipes and extending through said balls and into the boiler. 55

5. In a tube cleaner the combination of a supply pipe, a conduit extending from said pipe, a stand pipe connected to the conduit, an outlet nipple extending from the stand pipe, a movable supporting spindle for the 60 stand pipe and a flexible connection between said spindle and the stand pipe.

Signed at the borough of Manhattan, in the county of New York and State of New York, this 26th day of May, A. D. 1911.
